UNITED STATES PATENT OFFICE

169,237

HYPODERMIC SYRINGE

Eric Barrett and Altina Barrett, Beverly Hills,
Calif.; Altina Barrett, administratrix of said
Eric Barrett, deceased

Application November 23, 1951, Serial No. 17,511

Term of patent 14 years

(Cl. D83—1)

To all whom it may concern:

Be it known that we, Eric Barrett and Altina Barrett, citizens of the United States, residing at 2881 Coldwater Canyon Drive, Beverly Hills, in the county of Los Angeles and State of California, have invented a new, original, and ornamental Design for a Hypodermic Syringe, of which the following is a specification, reference being had to the accompanying drawing, forming part thereof.

Fig. 1 is a top view of a hypodermic syringe embodying our new design.

Fig. 2 is a front or rear elevational view of the hypodermic syringe.

Fig. 3 is a side elevational view of the hypodermic syringe.

Fig. 4 is front or rear elevational view of the hypodermic syringe without the needle cap.

Fig. 5 is a side elevational view of the hypodermic syringe without the needle cap.

Fig. 6 is a bottom view of the hypodermic syringe without the needle cap.

We claim:

The ornamental design for a hypodermic syringe, substantially as shown.

ERIC BARRETT.
ALTINA BARRETT.
